ROLLING DOOR

William Malcolm Waddell, West Vancouver,
British Columbia, Canada

Application March 3, 1945, Serial No. 580,746

3 Claims. (Cl. 160—229)

1

My invention relates to improvements in rolling doors, the object of which is to provide a structure which is capable of being made of sheet metal or plastics.

One of the disadvantages of rolling doors such as the interlocking type is that to substitute a new slat for a worn or damaged one, it is necessary to dismantle the door and slide the slats longitudinally for the entire width of the door, which generally precludes the possibility of a repair being made without removal from its place of suspension. The invention here described can be similarly repaired by simply removing one guide and drawing the defective slat rearwardly and substantially parallel to the plane of the door. A further object of the invention is to provide a door in which the joints are so formed as to be tight against wind and rain.

The invention contemplates a structure made up of slats each having a concave and a convex edge, which mate with corresponding parts of adjacent slats to form a continuous hinge joint, as will be more fully described in the following specification and shown in the accompanying drawings, in which:

Fig. 1 is a perspective view of a portion of the door as seen from the inside.

Fig. 2 is a sectional detail view of a side roller.

Fig. 3 is a detail sectional view of a modified nut and bolt structure for hingedly fastening the slats together.

In the drawings like characters of reference indicate corresponding parts in each figure.

The door, generally indicated by the numeral 1, is made up of slats 2 which consist of a web or straight medial portion 3 having an inwardly bent substantially semi-cylindrical bead 4 on one edge and an outwardly bent bead 5, to be referred to hereinafter as an upper bead 4 and a lower bead 5 respectively.

The upper bead 4 is so formed as to define a transversely arcuate rib 6 which projects beyond the outer face 7 of the medial portion 3 of the slats, when the door is in extended position as shown in Figure 1 and the curvature of the upper bead is preferably somewhat in excess of 180 degrees so as to define a throat 9 slightly less than the inner dimension of said bead, so as to permit a round rod 11 of the same diameter as the inner diameter of the upper bead to be sprung into said upper bead if desired. The upper bead is provided at predetermined intervals of its length with transverse slots 12, the lower bead is provided at correlated intervals with apertures 13 and the rod 11 is provided with threaded openings

14, see Figure 2, into which bolts 16 are inserted. The heads 17 of these bolts 16 are screwed down into contact with the lower bead 5, by this means the lower bead of one slat 2 is held in rocking contact with the upper bead 4 of the slat next below between the rod 11 and the head 17 of the bolt 16.

The lowermost slat of a door is preferably provided with a channel strip 19 which is attached thereto by rivets, spot welding or other suitable means.

In order to provide that the door may run freely in side or jamb channels, not shown, without chaffing the faces of the slats 2, I provide at 15 opposite ends of certain of the rods a roller 21 which is of greater radius than the lower bead 5. These rollers are recessed into the edge of the door which is cut away as at 22 and 23 and are each supported on the shanks of a bolt 25 extended into the outer end of the rod 11 to which it is attached. The bolt 25 is preferably held against turning by a set pin 26.

In the modification shown in Figure 3, the bolts 16 are driven into short strips or nuts 28 which 25 are formed of sheet metal in the form of a channel having a web 29 and flanges 30, which flanges are inwardly curved until their edges 31 are close enough to be both engaged by the threads of the bolt 16 as shown. The web 29 of each nut is 30 tapped as at 32 to receive the thread of the bolt. When the bolt is suitably tightened up to its nut the edges 31 of the flanges 20 are drawn towards 35 each other, thus gripping the thread and coacting with the tapped opening 29 to form a lock nut, thus preventing any tendency of the bolts to become slack. By virtue of the pressure between the nut 28 and the upper bead being almost entirely applied in close proximity to the opening 40 through which the bolt passes, there is no tendency in tightening the bolt to distort the bead and impair its free rocking movement within the lower bead 5 of the slat next above.

It will be obvious that the door, as shown, could 45 be used for transverse opening and closing movement as well as for vertical movement.

What I claim as my invention is:

1. A rolling door comprising a plurality of slats arranged in edge to edge relation, each of said 50 slats having a web and curved upper and lower beads extending from the margins of said web, the curved upper bead of one slat forming a rocking contact with the lower curved bead of the next adjacent slat, one of said contacting beads being provided with spaced transverse slots and

connecting means extending through said slots and into the contacting curved bead.

2. A rolling door comprising a plurality of slats arranged in edge to edge relation, each of said slats having a web and curved upper and lower beads extending from the margins of said web, the curved upper bead of one slat forming a rocking contact with the lower curved bead of the next adjacent slat, a portion of the curved upper bead being bent to define a longitudinal rib along the outer face of the slat while its major peripheral portion lies at the inner side of said slat and means for rockingly connecting contacting beads together.

3. A rolling door comprising a plurality of slats arranged in edge to edge relation, each of said slats having a web and curved upper and lower beads extending from the margins of said web, the curved upper bead of one slat forming a rocking contact with the lower curved bead of the 20

next adjacent slat, a rod adapted to be seated in the upper curved bead, said beads having mated openings at intervals of their length, and bolts extended through said openings into the rod and 5 rockingly connecting contacting beads together.

WILLIAM MALCOLM WADDELL.
